UNITED STATES PATENT OFFICE

150,290

DESIGN FOR A PHOTOGRAPHIC VIEWER

Leo Frankel, Chicago, Ill.

Application November 6, 1947, Serial No. 142,333

Term of patent 14 years

(Cl. D61—1)

To all whom it may concern:

Be it known that I, Leo Frankel, a citizen of the United States, residing at Chicago, in the county of Cook and State of Illinois, have invented a new, original, and ornamental Design for a Photographic Viewer, of which the following is a specification, reference being had to the accompanying drawing, forming a part thereof.

In the drawing—

Fig. 1 is a front elevational view of a photographic viewer, showing my new design;

Fig. 2 is a side view looking at the left side of Fig. 1;

Fig. 3 is a side view looking at the right side of Fig. 1;

Fig. 4 is a plan view;

Fig. 5 is a rear view; and

Figs. 6 and 7 are perspective views taken from slightly different angles and on a reduced scale in comparison with the other views.

I claim:

The ornamental design for a photographic viewer, as shown and described.

LEO FRANKEL.
